[57] CLAIM

The ornamental design for a multiple desk accessory receptacle assembly, as shown and described.

DESCRIPTION

FIG. 1 is a perspective view of a multiple desk accessory receptacle assembly showing my new design;
FIG. 2 is a top plan view thereof;
FIG. 3 is a front elevational view thereof;
FIG. 4 is a bottom plan view thereof;
FIG. 5 is a left side elevational view thereof;
FIG. 6 is a right side elevational view thereof;
FIG. 7 is a rear elevational view thereof;
FIG. 8 is a top plan view of a second embodiment of the multiple desk accessory receptacle assembly;
FIG. 9 is a top plan view of a third embodiment of the multiple desk accessory receptacle assembly;
FIG. 10 is a top plan view of a fourth embodiment of the multiple desk accessory receptacle assembly;
FIG. 11 is a fifth embodiment of the multiple desk accessory receptacle assembly;
The views of FIGS. 8-11 not shown are substantially similar to those shown in FIGS. 3-7.
